UNITED STATES PATENT OFFICE.

JOSEPH W. KENNA, OF CHICAGO, ILLINOIS, ASSIGNOR OF ONE-HALF TO
REUBEN A. HITCHCOCK, OF SAME PLACE.

CHILD'S CHAIR AND CARRIAGE.

SPECIFICATION forming part of Letters Patent No. 249,365, dated November 8, 1881.

Application filed May 24, 1880. (Model.)

To all whom it may concern:

Be it known that I, JOSEPH W. KENNA, of the city of Chicago, in the county of Cook and State of Illinois, have invented a certain new and useful Improvement in Childrens' Chairs and Carriages; and I do hereby declare that the following is a full, clear, and exact description of the same, reference being had to the accompanying drawings, in which—

10 Figure 1 presents a side elevation of my invention when adjusted for use as a chair. Fig. 2 presents a side elevation of the same adjusted for use as a carriage, the rear leg and also the back rail being in part broken away. Fig. 15 3 is a plan view of the under side of the seat.

The same letters denote the same parts in all the figures.

My invention relates to that class of structures which are adjustable at pleasure, so as 20 to be either stationary chairs or wheeled carriages; and its object is to make such adjustments safe, convenient, and economical by means of the several devices and combinations of devices, which I will now proceed to describe 25 specifically.

The main frame of the chair has on each side a longer rail, A, and a shorter rail, B, crossing each other at *c*, where they are pivoted together, the longer rails A constituting the sides 30 of the back frame and the front feet, while the shorter rails B support the front of the chair-body and constitute the hind feet. The shorter rails B, with the exception of a slight backward curvature at the feet, are nearly straight 35 until just below the pivoted joint; thence they pass upward and forward in a wave-line having its convexity backward in the portion nearest the pivotal point, and forward toward the front end. The longer rails A are nearly 40 straight from the top to a point below the chair-bottom; thence they curve forward and downward through an arc of about sixty-five degrees having its concavity forward rather more than half way to their lower ends; thence 45 to the lower ends the curvature is reversed and takes a longer radius, so as to make an arc of somewhat less than forty-five degrees. This conformation of the rails, which brings the pivotal point farther back than it would otherwise 50 be, and thus lower down on each rail (lowest

on the rails B) and nearer to the points of attachment of the wheels, makes it possible to lock the hind wheels against the rails A, (which are on the inner sides of the rails B,) when the structure is arranged as a high chair, and also facilitates its transformation into a carriage without that inconvenient protrusion of the legs front and rear which would be incident to the ordinary forms. The hind wheels, D, whose diameters are about three times as great as those of the forward wheels, D', and whose centers are about four times as far above the ground in the high-chair arrangement of the rails, are connected by an axle whose ends *e* project through the navels of the wheels and are connected by the scimeter-shaped springs *f* to the lower and forward sides of the shorter rails B, the surface of attachment being both above and below the pivot. This arrangement, which results naturally from the lowness of the pivotal point on the rails B, strengthens the leg in that part where it is subjected to the principal strain. The forward wheels D' are connected by substantially similar springs, *f'*, with the lower and backward sides of the longer 75 rails A. These wheels are so placed that a line drawn from the extremity of the leg and at right angles to its general direction would pass considerably without the circumference of the wheel. The rails A are braced together by 80 stretchers or rounds *a*, *a'*, and *a''*, and the rails B by similar stretchers, *b*, *b'*, and *b''*. The round *a*, in combination with the back rails, A, forms a convenient handle by which the structure can be trundled when used as a carriage, and 85 by which it can be readily lifted and moved from place to place when used as a chair.

The chair-body has a back, G, independent of the back rails, A. Its arm-supports H are firmly attached to the seat I, and extend below it to form supports for a foot-rest, J. They are pivoted to the shorter rails B, preferably a little above the seat, which gives the carriage-body a lower and more convenient position. On the under side of the seat, near the 95 middle point of its rear edge, is pivoted a short bar, K. To each end of this is attached a rod or pin, *l*, whose length is equal to about half the breadth of the chair-seat. The farther end of each rod passes through a collar, *m*, at 100

tached to the seat. At a point near the inner side of the collar the rod has inserted in it one end of a spiral spring, *v*, which is coiled around the rod for rather less than half the length of 5 the rod, being restrained from going farther by another collar, *n*. The elasticity of these springs is sufficient, when no repressive force is applied, to push the rods outward, so that their ends will project slightly beyond the 10 sides of the seat. The spring at its attachment to the rod coming against the collar *m* prevents them from going farther. The bar *K* then stands at an angle of about forty-five degrees to the rear edge of the seat. Attached 15 to the bar *K*, however, is a handle, *o*, which passes up through the chair-seat and behind the chair-back, through an opening in which it has room to turn. A thumb-screw may be conveniently substituted for the handle shown 20 in the drawings. By turning this handle or screw the bar *K* may be set at right angles to the rear edge of the seat, so that the rods will be drawn in until their outer ends do not project beyond the sides of the seat. 25 On the inner side of each back rail, *A*, and just above the round *a'*, is attached a stop, *P*, having on the lower part of its rear edge the wall-like projection *q*, at right angles to the inner surface of the rail, and on its lower edge 30 the shelf-like projection *q'*, which extends downward and forward beyond the front edge of the leg. The side of *P* also has the outward and forward projection *p'*. It also has a hole corresponding to the socket *p* in the inner side of *A*. On the inner side of the same rail, and a little above its junction with the shorter rail *B*, is another stop, *r r'*, projecting forward of the longer rail, and having the projecting portion *r'* bent upward and outward. 35 Near the forward end of *r'*, and at a point where the distance from the corresponding projection on the opposite rail is somewhat less than the distance between the extremities of the two rods *l* when they are forced together, is a hole, *y*, just large enough to receive 40 the end of the rod *l*. Around the stretcher *b*, and directly under the forward part of the chair-seat, are coiled the ends of an elastic wire, *s s'*, the middle part *s* of which extends 45 backward and upward in a narrow loop till it touches the under side of the seat at a point considerably back of the center. The stiffness of this wire is sufficient to hold the chair-seat up against the weight of a child. A depression, *T*, in the under side of the seat admits the coiled portion of the wire when the seat is forced down on the round *b*. The round *b* also serves, in connection with the downward 50 extensions of the arm-supports, to prevent the 55 chair-body from tipping forward while in transition from one adjustment to the other, any depression of the front below the back edge of the seat bringing the extensions against the round, and thus arresting the motion. The 60 round or stretcher *b'*, connecting the shorter rails *B* just above the pivot *C*, operates as a stop to prevent the legs from spreading too 65

far, and also, in case the rods *l* and springs *v* should fail to operate, from coming too close together. This latter object may also be attained by causing the rear portion of the chair-arms to extend sidewise, so that the distance between their extreme portions shall be greater than that between the two back rails. So far as relates to keeping the two 70 legs in their relative places, the purpose of the stretcher might be answered by a pin or lug projecting from the inner side of each leg *B*. 75

To adjust the structure for use as a chair 80 simply the chair-body, being disconnected from the rest of the structure except where the arm-supports are pivoted to the upper part of the shorter rails, is pushed back at the same time that the longer rails are pushed forward until 85 the outer ends of the rods *l* catch in the sockets in the longer rails at *p*, the oblique projections *p'* and *q'* serving as guides to give the back of the seat the proper upward direction, correct any tendency to veer sidewise, and gradually by oblique pressure on the ends of the rods *l* force them in, so that without the necessity of turning the handle *o* they will slip within the longer rails until they come opposite the sockets at *p*, when the elasticity of the springs 90 *v* will force them into the sockets, and the chair-body is thus securely locked in position. The contact of the lower extremities of the arm-supports with the cross-bar or round *b* is an additional safeguard against the chair slipping too 95 far back. The forward motion of the upper part of the longer rails and the backward motion of the upper part of the shorter rails bring both into a position more nearly perpendicular, so that the extremities of the legs rest on 100 the ground, and the wheels *D* and *D'* are therefore raised slightly above it, so that the chair stands firmly on its legs. In this position the rear wheels, *D*, are brought into close contact with the lower side of the legs, so as to be secure against any accidental turning. 105

To convert this chair into a carriage the handle or screw is turned so as to draw the ends of the rods *l* out of the sockets at *p*. The body of the chair is then pushed forward and downward until the ends of the rods catch in the holes *y* on the stop *r r'*, the outer extremity of *r'* operating in substantially the same way as *p'* and *q'*, to guide the chair-seat and gradually force in the ends of the rods until they come 115 opposite the holes *y*, when the chair-body is again securely locked in position, as shown in Fig. 2. The spreading of the legs consequent on the release of the rods from the sockets *p* lifts their extremities from the ground, so that 120 the structure now rests on the wheels and is converted into a carriage. The elastic wire *s s'* prevents the chair-body from folding suddenly when released from its higher position 125 between the longer rails. 130

In changing from the carriage to the chair adjustment the forward motion of the upper ends of the longer rails, and consequent backward motion of the front feet is facilitated by

their forward wheels, D', which are so placed on the legs as to roll on the ground in the beginning of this motion for some time after the hind wheels (whose point of attachment is 5 higher) are lifted from it, and thus prevent the friction of the ends of the legs thereon.

What I claim as my invention, and desire to secure by Letters Patent, is—

1. The rails A and B, pivoted to each other crosswise, a chair-body pivoted in front to the rails B, the rods l, pivoted bar K, and collars m and n, arranged as described, at the back of the chair-body, and the sockets p and y, and guides p', q q', and r r', arranged as described, 15 on the rails A, all in combination, substantially as and for the purpose described.

2. In an adjustable chair, the rails B, of the main frame provided with the stretcher b, in combination with a chair-body pivoted in front 20 to said rails a little above the stretcher, and provided with arm-rests H, extending below the pivotal point and in front of the stretcher, substantially as and for the purpose described.

3. The rails A and B, shaped as described, 25 and pivoted to each other crosswise, in combination with front wheels attached to the back edges of the rails A, and hind wheels attached to the forward edges of the rails B, and with a chair-body attached in front to the rails B 30 above the pivotal point, and provided at the back with adjustable catches arranged to engage with stops arranged on the rails A at different heights above the same pivotal point, said rails A having above the pivotal point an 35 inclination considerably less than that of the rails B, substantially as and for the purpose described.

4. In a combined chair and carriage, the rails B, shaped as described, in combination with the rails A, pivoted thereto crosswise, 40 shaped as described, and having a considerably less inclination above the pivotal point than the rails B, and with the wheels D, attached as described, to the rails B, for the purpose of locking against the rails A when the 45 structure is used as a chair.

5. A combined chair and carriage having the main supports A and B, pivoted at C, a chair-body pivoted to the upper ends of the supports B and otherwise entirely detachable, 50 the elastic wire s s', the pivoted bar K, capable of turning by a handle or screw-rods, l, springs v, and collars m and n, detachably connecting the chair-body with the main supports, and the wheels D and D' attached to the 55 main supports, all in combination, substantially as and for the purpose described.

6. In a combined chair and carriage, the rails A and B of the main frame, shaped as described and pivoted to each other crosswise, 60 the rails A having a considerably less inclination than B above the pivotal point, in combination with the wheels D and D', attached to the opposite faces of the said rails near the middle and the lower end of said rails respectively, substantially as and for the purpose described. 65
